CONTAINER

Charles H. Erne, Maywood, N. J., assignor to
American Can Company, New York, N. Y., a
corporation of New Jersey

Application April 6, 1939, Serial No. 266,364

2 Claims. (Cl. 221—61)

This invention relates in general to containers and more particularly to an outer sheet metal container for holding and protecting an inner filled container and helping to dispense its contents.

While the present invention is adapted to be used in connection with a great many different types of containers filled with a variety of products, it is exemplified herein in connection with a scouring powder container having a fibre body and metal ends. Such powder containers are usually kept in or about kitchen sinks where they come in contact with water or moisture or wet hands which tend to soften and soil its fibre body and adversely affect its contents. Also the metal ends when exposed to this moisture have a tendency to rust.

It is an object of the present invention to provide an outer container, for receiving, holding and protecting a scouring powder or other inner filled container, which will effectively prevent its coming in contact with wet or moist surfaces and at the same time function as a convenient manipulating device for dispensing the contents of the protected inner container.

Another object of the present invention is the provision of such a holding and manipulating device which will keep the inner container in a steady, non-shifting position at all times.

Still another object of the present invention is the provision of such a holding and protective device, which is of attractive appearance and lends itself to ornamentation in colors or designs.

Numerous other objects and advantages of the invention will be apparent as it is better understood from the following description, which, taken in connection with the accompanying drawing, discloses a preferred embodiment thereof.

Referring to the drawing:

Figure 1 is a side elevational view of a preferred embodiment of the present invention with parts broken away and others in cross section to show details of construction.

Fig. 2 is a fragmentary sectional view showing a modified top construction; and

Fig. 3 is a top plan view of the container shown in Fig. 1.

Referring in more detail to the preferred embodiment of the invention exemplified in Fig. 1, A represents generally the outer container or manipulating device or holder and B the inner container to be protected and from which the contents are to be dispensed.

The outer container A comprises a sheet metal 55

body 11 having a full bottom 12 preferably permanently joined to it in a double seam 13. The bottom 12, inwardly of the double seam 13 has a countersunk wall, which is substantially flat except for an annular groove 14 concentric with the body wall and spaced inwardly from it. This groove is of a depth and width to snugly receive the bottom joint or seam of the inner container B.

The body 11 is provided with screw threads 15 around its upper annular margin adapted to be engaged by corresponding threads of the depending flange 16 of a clamping cover or ring 17. The latter, inwardly of its threaded flange 16, has a horizontal wall or shoulder 18, a depending inner wall 19 which is substantially parallel with the threaded flange 16 and terminates in an annular horizontal clamping flange 21, bent inwardly at substantially right angles to the wall 19 and adapted to bear down upon the top of the inner container B.

A loop shaped band 22, having attaching flanges 23, is secured to the side wall of the body 11, functions as a manipulating handle C, and completes the construction of the outer container.

The inner container B, exemplified as a scouring powder container, comprises a tubular or cylindrical body 24 made of fibre stock, a countersunk metal bottom or end 25 joined to the body by the usual crimp seam 26, and a metal top or end 27 also joined to the fibre body by a like crimp seam 28. In a scouring powder container the metal top 27 is provided with a series of sifter holes 29 through which the powder may be sifted.

Fig. 2 illustrates a modified top construction, with all the parts the same as those described in connection with Fig. 1, except that the depending inner wall 19 of the cover terminates in an inwardly offset and downwardly curved annular clamping flange 21' which engages the top seam 28 of the inner container.

In actual use the inner filled container B is inserted in the outer container A with the bottom seam 26 resting in the groove 14. The cover or ring member 17 is then threaded over the outer container until the flange 21 engages and clamps down upon the top 27, with the result that the groove 14 and the wall 19 which fits snugly within the seam 28, hold the inner container B against radial or lateral shifting and the flange 21 in the construction shown in Fig. 1 and the flange 21' in the construction shown in Fig. 2 hold the inner container clamped tightly against axial movement. It will be noted that the bottom 12 of the outer container being a full or solid one and being in permanent and liquid-

tight interlocked engagement with the body 11, effectively protects the inner container against water or moisture or other adverse elements. It will also be seen that the cover flange 21 or 21' being of narrow annular width will leave the sifter openings 29 fully exposed for dispensing the contents therethrough when the outer container is manipulated by its handle C into dispensing position.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A holder for dispensing containers, comprising a permanent outer container body threaded at its open upper end adapted to receive and hold against displacement an inner replaceable filled container of materially less diameter and having a countersunk top wall from which the contents are to be dispensed, said outer container having an imperforate bottom wall permanently secured thereto in a liquid tight joint, and an integral annular clamping ring having threaded engagement with the open end of said outer container and adapted to expose a portion of the inner container top for dispensing purposes, said ring terminating at its inner portion in a depending integral annular clamping flange spaced inwardly from said threadedly en- 35

gaged portion and adapted to peripherally engage within the top wall of said inner container and hold the same against lateral and axial movement and to clamp said inner container against said imperforate bottom wall when said ring is screwed home on said outer container body.

2. A holder for dispensing containers, comprising a permanent outer container body threaded at its open upper end adapted to receive and hold against relative displacement an inner replaceable filled container of materially less diameter and having a perforated countersunk top wall from which the contents are to be dispensed, 10 15 20 25 30 said outer container having an imperforate bottom wall permanently secured thereto in a liquid tight joint, said bottom wall having an annular groove spaced radially inwardly from the wall of the outer container and adapted to receive and hold against displacement the peripheral portion of the bottom of the inner container, and an integral annular clamping ring having threaded engagement with the open upper end of said outer container body to expose the perforated portion of the inner container top wall for dispensing purposes, said ring having an inwardly disposed integral depending annular flange spaced inwardly from said threadedly engaged portions and adapted to peripherally engage within the countersunk top wall of said inner container to clamp the latter between said flange and said bottom groove against lateral and axial shifting when said ring is screwed home on said outer container body.

CHARLES H. ERNE.
